[57] CLAIM

The ornamental design for a portable speech synthesizer for speech impaired individuals, substantially as shown and described.

DESCRIPTION

FIG. 1 is a top front perspective view of the portable speech synthesizer for speech impaired individuals showing my new design;

FIG. 2 is a top plan view thereof on an enlarged scale;

FIG. 3 is a side elevational view thereof on an enlarged scale;

FIG. 4 is a rear elevational view thereof on an enlarged scale;

FIG. 5 is a bottom plan view thereof on an enlarged scale;

FIG. 6 is an opposite side elevational view thereof on an enlarged scale;

FIG. 7 is a top front perspective view of a second embodiment of my new design;

FIG. 8 is a top plan view thereof on an enlarged scale;

FIG. 9 is a side elevational view thereof on an enlarged scale;

FIG. 10 is a rear elevational view thereof on an enlarged scale;

FIG. 11 is a bottom plan view thereof on an enlarged scale; and

FIG. 12 is an opposite side elevational view thereof on an enlarged scale.
